UNITED STATES PATENT OFFICE.

ALFRED B. SMITH, OF TOPEKA, KANSAS.

RIM-TOOL.

1,312,590.

Specification of Letters Patent. Patented Aug. 12, 1919.

Application filed February 13, 1919. Serial No. 276,755.

To all whom it may concern:

Be it known that I, ALFRED B. SMITH, a citizen of the United States, residing at Topeka, in the county of Shawnee and State of Kansas, have invented a new and useful 5 Rim-Tool, of which the following is a specification.

By way of explanation it may be stated that as a matter of knowledge it is somewhat 10 difficult to manipulate a divided wheel rim, for the purpose of removing a tire therefrom or for the purpose of mounting a tire thereon. The present invention aims to provide a simple tool whereby a rim may 15 be manipulated as and for the purposes above described, the structure comprising but few parts, and being unlikely to get out of order, the tool being so made that it is well adapted to withstand the severe usage 20 to which structures of this kind are subjected commonly.

It is within the province of the disclosure to improve generally and to enhance the utility of devices of that type to which the 25 invention appertains.

With the above and other objects in view, which will appear as the description proceeds, the invention resides in the combination and arrangement of parts and in the 30 details of construction hereinafter described and claimed, it being understood that, within the scope of what is claimed, changes in the precise embodiment of the invention shown can be made without departing from 35 the spirit of the invention.

In the accompanying drawings:—

Figure 1 shows in top plan, a device constructed in accordance with the invention; Fig. 2 is a side elevation wherein a modified form of the invention has been applied 40 to a wheel rim; Fig. 3 is an end elevation of the tool shown in Fig. 2; and Fig. 4 is a section taken approximately on the line 4—4 of Fig. 2.

Referring to Fig. 1 of the drawings, the tool is shown as comprising a loop 1. Screws 2 are oppositely threaded as shown at 3, into the ends of the loop 1 and terminate at their outer ends in broad end heads 4 having reduced hooks 5, the structure be-

ing, in substance, a turn buckle. It will be obvious that the hooks 5 may be engaged with oppositely disposed portions of a wheel rim and that, by a proper manipulation of the loop 2 the ends of the wheel rim 55 may be moved with respect to each other, to effect a contraction or an expansion of the rim.

Passing to the modified form of the invention shown in Fig. 2, there is provided a 60 first loop 6 having oppositely disposed grooves 7, in which a carrier or ring 8 is mounted to rotate, the ring comprising parts 9 and 10 having flanges 11 connected by rivets 12 or in any other suitable way. 65 The part 10 of the ring or carrier 8 is supplied with an extension 14 on which one end of a second loop 15 is journaled, the second loop being retained on the extension 14 by means of a head 16 fashioned on the extension, all of which will be clear when Figs. 2 and 4 are compared. Screws 17 are oppositely threaded as shown at 18, into the ends of the first loop 6 and are provided at their outer ends with broadened heads 19 70 having reduced hooks 20. A screw 21 is threaded into the outer end of the second loop 15, as shown at 22, and terminates, at its outer end, in a broadened head 23 having a reduced hook 24. The hooks 20 and 24 are engaged with a wheel rim 50, at 75 spaced points, and, obviously by manipulating the loops 6 and 15, a movement between the ends of the rim 50 will be brought about. It is to be observed that the loop 15 has an 80 axial rotation on the extension 14, a swivel butt being formed. Further, the loop 15, together with the screw 21 may be swung transversely of the first loop 7, the carrier or ring 8 rotating in the grooves 7. The 85 structure, therefore, is such that the device will adjust and adapt itself readily to a wheel rim.

Having thus described the invention, what is claimed is:—

A rim tool comprising angularly disposed first and second loops; means for mounting the inner end of the second loop on the intermediate portion of the first loop for swinging movement about the first loop and 100

for rotation on an axis; screws oppositely threaded into the outer ends of the first loop, and a screw threaded into the outer end of the second loop, the screws being provided with rim-engaging means.

In testimony that I claim the foregoing

as my own, I have hereto affixed my signature in the presence of two witnesses.

ALFRED B. SMITH.
